UNITED STATES PATENT OFFICE.

HENRY H. CUMMINGS, OF MALDEN, MASSACHUSETTS.

SPEED-CHANGER.

SPECIFICATION forming part of Letters Patent No. 623,139, dated April 18, 1899.

Application filed January 10, 1898. Serial No. 666,184. (No model.)

To all whom it may concern:

Be it known that I, HENRY H. CUMMINGS, of Malden, county of Middlesex, State of Massachusetts, have invented an Improvement in 5 Speed-Changers, of which the following description, in connection with the accompanying drawings, is a specification, like letters on the drawings representing like parts.

My invention relates to improvements in 10 speed-changing mechanism whereby a machine which is operated from a continuously and uniformly running shaft in usual manner may be started at desired minimum speed, the speed being varied as required until the 15 machine is to be stopped.

It is desirable and, in fact, necessary in operating a large variety of machines that the machine shall be started slowly rather than suddenly at full working speed and that when 20 started the speed may be made faster or slower, as may be desired. Accordingly I have invented means by which the operator may through a starting-lever start the machine slowly and then by continuing the movement 25 of the said lever may increase the speed as desired, the machine being slowed down and stopped by a reversal of said lever.

The details of construction of my invention are set forth in the accompanying description, 30 reference being had to the drawings, and the invention is more particularly defined in the appended claims.

In the drawings, Figure 1, in side elevation and partly in section, the drive-pulley being 35 omitted for clearness, and Fig. 2, in front elevation, show my invention applied for purposes of illustration to a sewing-machine, the latter being largely broken away, sufficient thereof being shown to enable the operative relations of the parts to be understood. Fig. 3 is a top plan view of Fig. 2, the table and its supported mechanism being removed. Fig. 4 is an enlarged central vertical cross-section of the speed-changer.

For convenience of illustration I have herein shown my invention in connection with a sewing-machine A, supported on a table A', my invention being shown as applied to speed-changing mechanism of the variety heretofore 50 patented to me, in which a drive-pulley B, operated by a belt b from a main driving-shaft, is mounted loosely on a stud C, carried by a

central hanger D, a similar pulley E being loosely mounted on the opposite end of said stud, the pulley E being driven by the pulley 55 B through the action of the interposed friction-rolls F F' against the annular concave friction-surfaces B' E' of the pulleys.

The rolls F F' are shown as mounted loosely on horizontal studs at the lower ends of arms 60 f f', suitably pivoted at their upper ends, said arms having intermeshing segmental gear-teeth or other connections G G' fixed on their upper ends above the branching arms d d' of the hanger D. These gears are normally held 65 outturned, as shown in Fig. 3, by a suitable spring H, engaged at one end to the lever or arm g' of and connected to the gear G' and at its other end to a pin d^x in the arm d of the hanger, a stop d² being provided on the arm 70 d' to be engaged by a lug g² to limit the outward swing of the gears G G'.

The power-transmission rolls F F' are hung loosely between the pulleys B and E', so that when the latter pulley is tightly pressed toward the drive-pulley B motion is communicated to it frictionally through the rotation 75 of said rolls.

A coupling device or lever I, fixedly pivoted at i, is provided, preferably, with an 80 adjustable head i', clamped in its free end to bear on a cap e, closing the outer end of the sleeve-like hub e' of the driven pulley, a spring J, compressed in a socket in the hanger D, bearing against one end of the lever I and tending to swing the head i' against the cap e, as will presently be more fully described.

K designates the operating or starting-and-stopping lever, pivoted at k to the hanger, it 90 being provided with a stopping-brake k', offset, as shown in Fig. 2, to engage the driven pulley E' when it is desired to slow down or stop the machine, the lever K being operated in any convenient or desired manner, a foot-treadle L, vibrated on pivots l, being herein shown for such purpose, it being connected to the lower end of lever K by an adjustable headed stud l', working freely in a slot l² of the upright portion of the treadle. The upper 100 free end of lever K has an overhanging finger k³, adapted to engage one end of the lever I and hold it down against the spring J mentioned, and a shoulder k⁴ to engage arm g' of gear

G' when the lever K is moved back out of its engagement with lever I.

From the foregoing description it will be evident that, the parts being in the relative 5 positions shown in the drawings, if the operator depresses the treadle L, thereby throwing the lower end of lever K to the rear, the upper end of said lever will be thrown forward, withdrawing the finger k^3 from its holding engagement with the arm or lever I, permitting the spring J to swing the lever I at once against the pulley E', thereby starting the machine by the engagement of the pulley E' with the rolls F F', the latter being frictionally driven by the pulley B. The machine having thus been started, if it is desired to run it faster the speed is increased by continuing to depress the treadle, thereby bringing the shoulder k^4 into engagement 10 with arm g' and swinging the gears G G' to the left, Fig. 3, and consequently separating the points of contact of the rolls F F' with the drive-pulley B and moving closer together the opposite points of contact thereof 15 with the driven wheel E', or, in other words, the path of travel of the rolls is increased in circumference on the drive-pulley and correspondingly decreased on the driven pulley, thus gaining the required speed. Upon stopping the machine the raising of the treadle either positively by the foot or automatically by spring H operates first to permit the spring H to swing the gears G G' to the right, as shown in Fig. 3, thereby correspondingly 20 turning the rolls and slowing down the machine, then to permit the finger k^3 to engage the lever I and withdraw the latter from engagement with the driven pulley, and finally to apply the brake k' to the driven pulley 25 and positively stop the machine. All these successive operations are accomplished simply by one operation of the treadle.

I have shown the rolls and their gears or such other connecting devices as may be employed arranged to start the driven pulley at the same initial speed as that of the drive-pulley; but it is evident that this may be varied as desired by changing the inclinations 45 of the rolls and by changing the arrangement and connections of the gears or their equivalents used; also, I have shown various pivoted members or levers; but it is evident that these members need not be pivoted, as other movements may be substituted.

50 It is to be borne in mind that my invention is intended for a wide range of uses, being shown in connection with a sewing-machine for convenience merely; nor is it limited to the particular variety of speed-changing mechanism herein shown, inasmuch as any other suitable mechanism may be substituted.

55 By one simple movement of the lever K the machine is started at slow speed and gradually increased in speed, as desired, and by a simple reverse movement of said lever the machine is slowed down, the power is thrown off, and the machine is stopped. This cycle

of movements takes place invariably, so that, for instance, a careless workman cannot suddenly couple the machine for its top-most speed and thereby break the machine or ruin the material being operated upon or perhaps injure himself, but the machine will start and stop in one way only—viz., with an initial and final slow movement.

70 Various changes in details of construction, arrangement, and combination of the parts of my invention as herein embodied may be resorted to without departing from the spirit and scope of my invention.

75 Having described my invention, what I claim as new, and desire to secure by Letters Patent, is—

1. The combination with power mechanism, a machine to be operated, and intervening speed-changing mechanism, of an operating member, and a spring-actuated device for coupling said machine to said speed-changing mechanism, said device being separate from and independent of said speed-changing mechanism, said operating member normally holding said coupling device in inoperative position, substantially as described.

80 2. The combination with power mechanism, a machine to be operated, and intervening speed-changing mechanism, of an operating member, a coupling device for coupling said machine to said speed-changing mechanism, said coupling device being separate from and independent of said speed-changing mechanism, and automatic means normally maintaining said coupling device in inoperative position, substantially as described.

85 3. The combination with power mechanism, a machine to be operated, and intervening speed-changing mechanism, of an operating member, a brake actuated by said operating member to stop said machine, a coupling device to couple said machine to said speed-changing mechanism, and automatic means normally maintaining said coupling device in inoperative position, substantially as described.

90 4. A positively-driven friction-pulley, a variable-speed pulley mounted concentrically therewith, friction-rolls journaled between said two pulleys on arms extending beyond said pulleys, to rotate in planes perpendicular to the faces of said pulleys, intermeshing toothed segments fast on the projecting ends of said arms, an operating member for positively moving said gears in one direction, and automatic means for giving an opposite movement, substantially as described.

95 5. A positively-driven friction-pulley, a variable-speed pulley journaled face to face with said pulley, friction-rolls between and to engage said two pulleys, said rolls having their shafts projecting from arms extending beyond said pulleys, intermeshing segmental gears fixed on said arms, a lever extending from one of said gears, a spring normally mov-

ing said lever in one direction, and an operating member for moving it in an opposite direction, substantially as described.

6. A speed-changing mechanism comprising a drive-pulley, a driven pulley, a friction-roll between said pulleys, the driven pulley being normally out of driven engagement with said roll, a coupling device to move it into driven engagement with said roll and said drive-pulley, said roll having a lever for shifting the position of said roll between said pulleys, an operating member normally engaging said coupling device and holding it out of coupling engagement, said member being arranged in the path of said lever and between the latter and said coupling device, substantially as described.

7. A speed-changing mechanism comprising a drive-pulley, a driven pulley, a friction-roll between said pulleys, the driven pulley

being normally out of driven engagement with said roll, a coupling device to move it into driven engagement with said roll and said drive-pulley, said roll having a lever for shifting the position of said roll between said pulleys, an operating member normally engaging said coupling device and holding it out of coupling engagement, said member being arranged in the path of said lever and between the latter and said coupling device, and a spring normally holding said lever in engagement with said operating member, substantially as described. 25

In testimony whereof I have signed my name to this specification in the presence of 30 two subscribing witnesses.

HENRY H. CUMMINGS.
